UNITED STATES PATENT OFFICE.

CHARLES B. KELLOGG, OF CHICAGO, ILLINOIS, ASSIGNOR OF ONE-HALF TO EUGENE U. KNIGHT, OF CHICAGO, ILLINOIS.

DISPLAY DEVICE AND METHOD OF FORMING SAME.

1,385,834.

Specification of Letters Patent. Patented July 26, 1921.

Application filed January 31, 1921. Serial No. 441,109.

To all whom it may concern:

Be it known that I, CHARLES B. KELLOGG, a citizen of the United States, residing at Chicago, Illinois, have invented certain new and useful Improvements in Display Devices and Methods of Forming Same, of which the following is a specification.

This invention relates to a display device for illustrating advertising matter, and the 10 method of forming the same.

Among the objects of my invention are to provide a display device of improved construction; to provide a display device which in its finished form will have the appearance 15 of including a container or actual packet of the goods being advertised; to provide in a device of the class described an effective and quickly operated locking arrangement; the provision of a device of the class described 20 stamped in the form of a flat blank to facilitate the ready application of printed matter thereto prior to the bending of the device into finished form; a novel method of forming the finished article; the provision 25 of a display device of simple, economical and efficacious construction and arrangement; and such further objects, advantages and capabilities as will later more fully appear.

30 My invention further resides in the combination, construction and arrangement of parts shown in the accompanying drawings, and while I have illustrated therein a preferred embodiment, I desire the same to be 35 understood as illustrative only, and not as limiting the scope of my invention.

In the drawings:—

Figure 1 is a perspective view of a display device embodying my invention.

40 Fig. 2 is a rear elevation, the right hand side of this view being shown partly in section for the sake of clearness.

Fig. 3 is a horizontal transverse section on the line 3—3 of Fig. 2.

45 Fig. 4 is a vertical section on the line 4—4 of Fig. 2.

Fig. 5 is a plan view of the blank from which my device is formed, and shows the same prior to bending into final form.

50 Referring to the drawings it will be seen that my improved display device as seen in Fig. 1, is adapted, as hereinafter more fully set forth, to be bent and locked in the finished form, to have the appearance of including a 55 container or actual packet of the goods be-

ing advertised, which packet in this figure is for the sake of illustration shown in the form of a one pound container or carton for butter. The container or packet included, may, of course, assume different forms, to 60 represent various materials to suit the particular customer.

Referring more particularly to Fig. 5, it will be seen that my device may be stamped in flat form from any suitable material such 65 as cardboard, or the like, and comprises in general the back or upright portion 1, the base portion 2, which is secured integrally to portion 1 by the connecting portion 3, which latter will represent the upper portion 70 of the container or packet. The back portion 1 includes the side portions 4 and 5, which are formed at their edges at the desirable position with the locking projections or keys 6 and 7, respectively. Side portions 75 or wings 4 and 5 are bent along lines *a* and *b* rearwardly at an angle as shown in Fig. 3. Portion 1 is separated from the base portion 2, along the lines 8, 9, 10 and 11 to facilitate bending along the dotted lines 12 80 and 13, to throw the portion 14 into a position spaced outwardly from back portion 1, to represent the front of the packet, while the portion 3, as above stated, will form the top of said packet. Base portion 2 will at 85 the same time have the outwardly extending wings 15 and 16 bent backwardly along lines 17 and 18 to bring the upwardly extending ears 19 and 20 back of upright portion 1, to position slots 21 and 22 in registry with 90 the locking tongues 6 and 7, whereby the latter may be inserted through these slots to lock wings 19 and 20, in position as shown more clearly in Figs. 2, 3 and 4. These bending operations will bring the bottom edges 95 of vertical portion 1 in substantial alinement with the bottom of base 2, to permit the device to stand on a substantially level supporting surface, as will be more readily understood from an inspection of Figs. 1, 2 and 4. 100

Prior to bending the blank shown in Fig. 5, the same may be passed through a printing press, or treated in any other way desirable, to print upon the various portions thereof the advertising matter required, 105 which as illustrated in Fig. 1 is in the present instance the simulation on horizontal surface 3, portion 14, and parts of side wings 15 and 16, of a packet of butter, to have the appearance of the actual attachment to the 110

back portion 1, of a carton of this material. At the same time the back portion will have added thereto any advertising matter referring to the packet being displayed, and 5 when the wings are locked together, as set forth above, the device is ready to be placed in a show window or elsewhere as desired for advertising purposes.

This device, as will be readily appreciated 10 from the above description, is cheap to manufacture, can assume any desired form representing various advertisements, and because of my novel locking arrangement can be rigidly locked in final form with ease and 15 effectiveness.

While I have shown in the present illustration a packet of butter and advertising relating thereto, it is, of course, understood that any material desired may be represented and advertised on this device.

Due to the angular arrangement of locking wings 15 and 16, the locking tongues 6 and 7 when passed through slots 21 and 22 will be of such nature as to very effectively 25 hold these parts together, and because of the simplicity of arrangement the blank may be quickly bent into final form and the parts effectively locked together.

Having now described my invention, I 30 claim:—

1. A display device comprising a back portion having angularly and rearwardly bent side wings provided with locking extensions, a forwardly extending base portion 35 having a top and rearwardly bent side wings, said last mentioned wings extending back of said back portion and having means coöperating with said locking extensions to lock the parts together.

40 2. A display device comprising a back portion having angularly and rearwardly bent side wings provided with locking extensions, a forwardly extending base portion having a top and rearwardly bent side wings, said last mentioned wings extending back of said back portion and having means coöperating with said locking extensions to lock the parts together, said means comprising 45 slots in the base portion wings through which said locking extensions pass angularly respectively.

3. In a display device of the class described, a back portion having rearwardly and angularly extending locking tongues, a base portion having rearwardly extending 55 wings provided with slots adapted to receive said locking tongues, and a connecting portion between the said back portion and said base portion to represent the top of a container, the front and sides of the container 60 being represented by the front and portions of the wings of said base portion.

4. An advertising device representing an upright advertising space and a carton of the material being advertised, comprising an 65 upright portion adapted to receive advertising matter, a base portion having a front face, and rearwardly extended side portions to represent the front and the ends of said carton, and a connecting upper portion to 70 represent the top of said carton, said last mentioned portion being integrally connected with said back portion, said rearwardly extending portions of the base extending behind said back portion, and means 75 to lock the latter with relation to said back portion, said device being capable of being laid out flat to receive the advertising printing on one side only.

5. In a display device a back portion having rearwardly and angularly extending arms, a forwardly extending portion, wings extending from said forwardly extending portion through and a substantial distance back of said back portion, and means for 85 locking said wings and said arms together back of said back portion.

6. In a display device a back portion adapted to receive advertising matter, a forwardly extending portion representing a 90 carton of the material being advertised, wings extending from said forwardly projecting portion back of said back portion, and means for locking said wings and said back portion together, said means comprising locking tongues extending rearwardly at an angle from said back portion and passing through apertures in said wings at the rear of said back portion.

In witness whereof I hereunto subscribe 100 my name to this specification.

CHARLES B. KELLOGG.
